REFRIGERATING APPARATUS AND
METHOD

Charles L. Jones, Pelham, N. Y., and Howard S. McIlvain, Belleville, N. J., assignors, by mesne assignments, to Adico Development Corporation

Original application April 27, 1931, Serial No. 533,036. Divided and this application May 7, 1931, Serial No. 535,784

17 Claims. (Cl. 62—91.5)

This application is a division of our co-pending application Serial No. 533,036, filed April 27, 1931, for "Refrigerating apparatus and methods".

Our present invention relates to refrigerating apparatus and methods particularly adapted for use in connection with solid carbon dioxide as the refrigerant. By our invention, we simplify the apparatus and make it readily adaptable for refrigerators of widely varying types and sizes, and for widely varying conditions of use of any refrigerator in which the invention has been embodied.

An important feature is to make the solid carbon dioxide and its container respond quickly and effectively for re-chilling the atmosphere of the refrigerator, when suddenly over-heated as by frequent use of side-opening doors of refrigerated delivery trucks, but many of its features may be effectively utilized in other types of refrigerators, as for instance, household, display-case, or storage room refrigerators; also refrigerator-cars and "less-than-carload lot" containers.

One object of the invention is to provide a novel container for the solid carbon dioxide, constructed with a view to collecting heat from a comparatively wide area of the atmosphere of the refrigerated space and preferably from the upper or warmer region of said space; preferably also to collect it rapidly through metal surfaces and to conduct it to the interior of said container through an all metal path.

When the exterior surface of the metal is exposed to the atmosphere directly, its response to changes of temperature of the atmosphere is very rapid as compared with the much slower response of metal containers that absorb heat through heat insulation. The less the exterior insulation and the further the collected heat has to travel through the all metal path, the more closely will the collecting surface tend to follow the temperature of the contacting air rather than that of the refrigerant source. Consequently, the quicker and more effective the response will be.

In certain special cases, where low temperature or a high rate of refrigeration is required, the refrigerant container may be used without any insulation either outside or inside, the solid carbon dioxide resting directly on the metal bottom of the container. On the other hand, interior insulation as by wrapping the blocks of solid carbon dioxide in one or many thicknesses of paper or of corrugated paperboard between the solid and the bottom of the container may be availed of to slow down the rate of sublimation of the solid,

thereby increasing the effective refrigerant temperature of the walls of the container and its remote collecting surfaces, without proportionally decreasing the sensitiveness with which said surfaces will collect and deliver the heat.

One important factor is that whatever may be the basic refrigerant evaporation rates thus predetermined, it is seldom possible to avoid formation of frost on the heat collecting surfaces. The lower the temperature of these surfaces, the more frost they are likely to collect, and such frost layer is variable and therefore unreliable exterior insulation tending to make the exterior refrigerant surface vary from approximately the freezing point of water when the frost is very thick, down to say 50° or more below zero F., which may be the temperature of the bottom of the container when it is free from frost.

It will be evident that by having metallic heat conducting flanges and fins of large area extending into contact with relatively remote parts of the atmosphere of the refrigerated space, particularly at a high level therein, the coldest spot will be at the bottom of the container, and that the temperatures will be progressively higher toward the more remote edges of said heat collecting flanges or fins. In a particular case, the latter might be at or above zero F. while the bottom of the metal container would be 50° or more below zero. In such case, the frost formation will be thinnest toward the remote edges, and progressively thicker along the lines of heat flow to the bottom of the container on which the solid carbon dioxide is supported. It will be evident that by this distribution of the insulating frost, the direct heat absorbing effect of the cold bottom of the container may be decreased to or below that of the remote heat collecting surfaces which are frosted much less, or not at all. In practice, it is found that the remote collecting areas seldom collect enough frost to seriously impair their sensitiveness or prevent them from transferring heat at the rates required for evaporating refrigerant and developing refrigerant values at the desired rate.

In some cases we have made the metal of the refrigerant container and heat collectors relatively thin and have effected the high level heat collection by circulating the evaporated gas in conduits, preferably thin and flat, arranged around the upper angles of the ceiling and side walls.

However, in the preferred case, the gas circulating conduits are dispensed with; the metal of the container and its heat collectors is made

relatively thick so that the metal will afford substantial heat storage as well as heat collecting capacity; and said collectors are extended as far as may be desired, sometimes to the walls or 5 even downward on the wall.

In any case, the gas may be discharged inside or outside the refrigerated space, but preferably outside, either to the exterior atmosphere or into the insulation container between exterior walls 10 of the refrigerator, to there serve as drying and insulating as well as somewhat refrigerant medium.

The above and other features of my invention will be more evident from the following description 15 in connection with the accompanying drawings, in which

Fig. 1 is an enlarged plan view of a form of the bunker designed for various uses in accordance with our present invention;

20 Fig. 2 is a side elevation of the bunker, partly in section and showing it attached to the roof of a truck or other refrigerator chamber;

Fig. 3 is a vertical section of the bunker, taken on the line 3—3 of Fig. 1;

25 Fig. 4 is a vertical section taken on the irregular line 4—4 of Fig. 2;

Fig. 5 is a perspective view of the refrigerant insulated as by wrapping in a number of thicknesses of paper; or by merely supporting on a 30 layer of insulation such as corrugated paper board; or both;

Fig. 6 is a similar view showing a single chamber with two bunkers;

35 Fig. 7 is a horizontal section of the adjacent refrigerator chambers each corresponding to Fig. 2 but with the roof removed to show the bunkers in place, the bunkers being different in detail; and

40 Fig. 8 is a vertical section of refrigerator chamber, the interior and a modified form of bunker being shown in perspective.

The refrigerated space as shown in Figs. 6, 7 and 8, may be the body of an ordinary motor truck or any other refrigerator, and may have 45 any desirable number of doors 3 and, preferably in the top, there are hatchways 4, Fig. 2, each having directly thereunder an opening 6 through which the refrigerant is charged into the bunker 8.

50 The refrigerated space is preferably made gas-tight in any conventional manner and we have found it very effective and economical to provide inner and outer gas-tight metallic walls 9 and 10 with any desirable thickness of good insulating material 11, such as kapok or cork, between the said gas-proof walls 9 and 10.

While the bunker 8 may be made of galvanized iron, copper or other metal, or may be fabricated from sheet metal, it is preferably made of aluminum and cast at one operation, thus minimizing the cost and doing away with the necessity for labor in assembling different parts. The aluminum, or aluminum alloy is comparatively 65 cheap, is of exceptionally good heat conducting quality. A shallow bunker of convenient capacity may have its body portion, say, 50" x 14" x 8". The walls of the casting may be, say, $\frac{1}{8}$ inch thick, but in any event, the metal may be made 70 thick enough to afford ample cross-section for flow of heat; also to afford great heat storage capacity, which is another way of saying that, when cold, it represents readily and locally available refrigerating capacity which is effective for 75 absorbing heat when the refrigerated atmosphere

is suddenly warmed, as by opening the service doors.

The bunker 8 has integral bottom and side walls, and is closed in by the gas-tight top 18, except for the opening 6, to permit of charging 5 of same with solid; and said opening has upright walls 15 forming a gas-tight well or combing that projects up into the hatchway and is sealed therein by rubber or other gas-tight packing or cement. The upper surface of the bunker is preferably 10 spaced away from the ceiling any predetermined distance by provision of cross ribs 23, which may be made, say, one-half inch thicker than the balance of the top 18 so that they not only provide for a space of definite thickness between the 15 bunker and the ceiling of the refrigerator, but also afford a stronger portion through which the bunker may be fastened to the ceiling, the fastening being accomplished by the screws or bolts passing through the openings 24. 20

The bunker 8 is preferably of cast aluminum or aluminum alloy, and in a particular case the various parts were approximately $\frac{3}{8}$ inch in thickness. It has a plurality of heat collecting extensions including fins 17, extending from the 25 sides and having the largest portion of their heat collecting area, in direct heat-imparting relation to a relatively high level portion of the bunker. The high level heat collecting surface is further increased by extending the top 18 of the bunker 30 beyond the vertical sides 19 to form lateral flanges 18a and preferably the fins 17, are formed as brackets supporting said flanges and operating as short circuiting, all-metal conducting paths for flow of heat directly to the lower, colder portions of the walls of the bunker. 35

In Fig. 2, the bunker is shown in position in a section of the roof of a refrigerator, the hatchway thereof being closed, substantially gas-tight, by a closely fitting top 1. It also shows how the 40 raised portions 23 provide a circulating space 26 between the ceiling and the top of the bunker.

The inside surface of the bottom of the bunker may be formed with raised ribs 28 which may take the form of cross-grids or both cross and 45 lengthwise or may be any other convenient form just so they will offer resistance to the sliding motion of the refrigerant caused by the jarring or jolting of a truck or refrigerator car.

The openings shown at 29 and plugged by the 50 plugs 30 are placed at any convenient location and may be used for hooking-up an automatic temperature control, valve operation, or the like.

Our invention can be used either for frozen or non-frozen products and because of the absence of insulation, in the preferred form, around the bunker itself, a very low temperature can be reached in a minimum of time, and by the simple expedient of placing varying amounts of insulation, either around the solid carbon dioxide 20, 60 as shown at 21, Fig. 5; or between it and the metallic bunker, as shown at 22, we can accurately control the heat absorption, thus controlling the sublimating rate of the solid carbon dioxide and still having the advantages of an un-insulated bunker when the same is desirable. 65

The heat is conducted from the refrigerated atmosphere to the refrigerant through the un-insulated metal walls, and the heat from more remote and warmer portions is conducted directly 70 to the bunker through the heat collecting extensions 18a, 17. The usual top to bottom thermo currents of the atmosphere of the refrigerated space will be set up but will not be as localized in this case as in other refrigerators of this 75

general type, because the relatively great heat absorbing area in the upper or normally warmest region will offset the natural tendency of the bottom to become much colder than the top, and as this difference in temperature between the different regions is what tends to set up such currents they will therefore be greatly diffused.

The heat absorbing area is distributed over a wide space, which space may include practically all of the ceiling area, this region normally tending to be the warmest and most difficult to refrigerate. Another advantage is that the various parts are placed almost entirely out of the path of incoming and outgoing products and they will not be subjected to the hazard of injury due to the jolting or sliding around of the cargo while the vehicle is in motion. This also obviates the necessity for erecting a protecting wall between the lading and the ducts, when a duct system is used; and the ducts may be confined to a high level.

In Fig. 7, the bunker of Figs. 1 to 4 is shown as varied by having the laterally extending flanges 18b as much wider as may be desired. Also the end of the bunker is flanged as at 18c, in addition to the side flange shown in the other figures. In the left compartment of Fig. 7, we have shown how instead of widening the integral flanges, supplemental flanges 18d may be bolted or riveted in firm heat conducting contact with the flanges 18a. These supplemental flanges may be extended to the side walls of the refrigerator, as shown, and the outer edges may be turned down and secured to said side walls, if desired.

In Fig. 6, the arrangement is like that shown in Fig. 7, except that the bunkers are supposed to be of the construction shown in Figs. 1 to 4, and the entire distance between them is bridged by a supplemental sheet metal piece 18x.

In all cases, the supplemental extension may be a casting, or sheet aluminum or sheet copper, or any other desired metal.

In both Figs. 6 and 7, the gas taps 40, 41 are shown as connected to gas discharge pipes. Pipes 42 each discharge into the insulation through cock 43 and pipes 44 discharge gas to the exterior but each is controlled by a three-way cock, 45, whereby the gas may be discharged either outside or into the refrigerated space.

Fig. 8 is a simple diagrammatic view showing how the interior of the refrigerator may appear when it is the proper size for a single bunker. In this case the entire bunker construction including heat collecting flanges and brackets may be the same as in Figs. 1 to 4. However, we have utilized this view to show how the bunker may be tapped and supplied with a coupling plate 31 for a low level gas outlet 32; also how the sides may be similarly provided with outlet couplings 31a for high level gas conduit connections. Either of these connections may be used for flat gas flow conduits leading to any desired part of the refrigerator space and if desired, a closed circuit of gas circulation may be conducted from the low level outlet 32 around the corners between the roof and side walls, in which case the gas may be returned through the side high level coupling 31a. It will be obvious that the coupling 31 and 31a may be removed and imperforate plates bolted on in their stead; in which case the construction will become to all intents and purposes, the same as that shown in Figs. 1 to 4.

In most cases we prefer not to discharge the gas into the refrigerated space because air is

lighter and gives a much more lively convection circulation to and from the metal heat collecting surfaces, thereby tending to more rapid equalization of temperature between the top and the bottom. This is highly desirable where service doors are frequently opened. Also pure air is desirable where the space must be entered for loading or unloading.

We desire to point out that our invention is susceptible of many changes, a number of which have been pointed out, and we do not mean to limit the scope of the specification or claims by the particular working or drawings here illustrated.

We claim:

1. A refrigerating apparatus including a heat insulated chamber, a heat conducting material container for a solidified gas refrigerant positioned at a high level therein in spaced relation to the walls of the chamber and uninsulated from the atmosphere to be refrigerated, said container having heat conducting extensions disposed horizontally from opposite sides of the container at a level at the top side thereof and extending to portions of the chamber remote from the container, and heat collecting fins below said extensions for conducting heat to the container.

2. A refrigerating apparatus including a heat insulated chamber, a metallic container for a solidified gas refrigerant mounted at a high level in the chamber in spaced relation to the chamber walls and uninsulated from the atmosphere in the chamber, said container having heat conducting extensions disposed horizontally from opposite sides of the container at a level at the upper side of the container, and said extensions extended from the container to opposite side walls of the compartment across the space in the chamber between the container and compartment walls.

3. A refrigerating apparatus including a heat insulated chamber, separate metallic containers for a solidified gas refrigerant mounted at a high level in the chamber adjacent but spaced from opposite walls, respectively, of the chamber, each of said containers in spaced relation to the walls of the chamber and uninsulated from the atmosphere to be refrigerated, said containers each having heat conducting extensions disposed horizontally from opposite sides thereof at a level at the top of the container, and the extensions on facing sides of the containers joined to extend across the space in the chamber between said containers.

4. A refrigerating apparatus including an insulated chamber, a metallic container for a solidified gas refrigerant supported at a high level in said chamber spaced from all the chamber walls for circulation of the chamber atmosphere completely there-around, said container uninsulated from the chamber atmosphere and having metallic heat conducting extensions horizontally disposed and extending from above the bottom of the container to remote portions of the chamber for conducting heat from such remote portions to the container and a refrigerant therein.

5. A refrigerating apparatus including an insulated chamber to be refrigerated, a container of heat conducting material adapted to receive a solidified gas refrigerant therein, said container mounted at a high level in said chamber spaced away from all of the walls of the chamber for circulation of air within the chamber completely there-around, and the said container having high heat conducting extensions extending from

15

- above the bottom of the container to the top thereof and terminating in extensions extending from the top of the container to relatively remote portions of said chamber.
5. 6. A refrigerating apparatus including an insulated chamber, a container of heat conducting material adapted to be charged with a solidified gas refrigerant in thermal relation therewith, said refrigerant container supported in the 10 chamber at a high level therein adjacent but spaced from the top wall and remaining walls of the chamber and uninsulated from the atmosphere in the chamber to be refrigerated, said container being of greater length than width and 15 having heat conducting extensions extending from the top of the longer sides of said container above the bottom thereof, to portions of the chamber relatively remote from said refrigerant container.
20. 7. A refrigerating apparatus including an insulated chamber, a container of heat conducting material adapted to receive a solidified gas refrigerant therein in heat exchange relation therewith, said refrigerant container mounted in the 25 chamber at a high level adjacent the top wall thereof and uninsulated from and in direct heat conductive relation with the atmosphere within the chamber, the said container being of greater length than width and having heat conducting 30 extensions extending horizontally from the longer sides of said container from a level near the top thereof, to portions of the chamber relatively remote from the container.
35. 8. A metallic container for a solidified gas refrigerant, having an opening through the top wall for access to the interior of the container, the container top side extended a considerable distance beyond the container side walls to provide metal heat conducting paths from locations relatively remote from the container, and heat collecting fins extending from the container side walls below said extended container top side.
40. 9. A relatively thick-walled, cast-metal container for a gas producing refrigerant, said container having a normally closed top opening for charging the container with refrigerant and the container walls being substantially without exterior heat insulation, the top side of said container being extended a considerable distance 45 beyond the side walls thereof to provide metallic heat conducting paths to the container from locations relatively remote from the container, and heat collecting fins extending from the container side walls below said extended top side of the 50 container.
55. 10. A metallic container for a solidified gas refrigerant, having the walls of the container without substantial exterior heat insulation, the top side of the container being extended a considerable distance beyond a side wall of the container to provide a metallic heat conducting path from a location remote from the container, and vertically disposed heat conducting fins extending from the container side wall in heat exchange 60 relation therewith and below the extended top side of the container.
65. 11. A metallic container for a solidified gas refrigerant, having the container walls without exterior heat insulation, the top side of the container being extended a considerable distance beyond a side wall of the container to provide a heat conducting path from a location remote from and out of substantially direct thermal ef-
- fect by the wall of the container, and spaced vertically disposed heat conducting fins extending from the wall of the container below said extended top side, the outer ends of the spaces between said fins being open and substantially 5 completely unobstructed through-out the depth of the outer ends of the fins.
70. 12. A metallic container for a solidified gas refrigerant, said container adapted to be mounted in a chamber to be refrigerated adjacent the top wall of the chamber, the container having the walls thereof without exterior heat insulation and being provided with a normally closed top side opening for charging the container with refrigerant, spacing means provided on the exterior of the upper side of the container for maintaining the container spaced from the top wall of a chamber in which mounted, said container having the top side thereof extended beyond a side wall thereof for a considerable distance to provide a heat conducting path from a portion of a chamber remote from the container, and heat conducting fins extending from the container side wall below the extended top side of the 25 container.
75. 13. A refrigerating apparatus including in combination, an insulated chamber to be refrigerated, a metallic container for a solidified gas refrigerant, mounted in said chamber at a high level adjacent the top wall of the chamber, said container being uninsulated from the atmosphere in the chamber and spaced from the top wall and remaining walls of the chamber for circulation of the chamber atmosphere completely around and over the container, and said container provided with heat conducting extensions disposed substantially horizontally from opposite sides thereof at a level adjacent the top of the container, said extensions extending considerable distances across the chamber to portions of the 30 chamber atmosphere remote and removed from the direct thermal effect of the uninsulated container.
80. 14. A refrigerating apparatus comprising an insulated chamber, a container for solid carbon dioxide at a high level therein and uninsulated from the atmosphere to be refrigerated, said container being of greater length than width and having high heat conducting extensions extending from the longer sides of said container and increasing in area from the bottom towards the 35 top, and from a point near the top of said container.
85. 15. A metallic container for a refrigerant, having an opening for access to the interior thereof and having the top side extending beyond the side walls thereof and heat collecting fins below and in contact with said extended top, and arranged at right angles thereto.
90. 16. A metallic container for a refrigerant, having an opening for access to the interior thereof and having the top side extending beyond the side walls thereof and heat collecting fins extending from said side walls below said extended top and being of increasing area towards the top.
95. 17. A metallic container for a refrigerant, having an opening for access to the interior thereof and having the top side extending beyond the side walls thereof and heat collecting fins extending at right angles from said side walls and 60 connected to said top.

CHARLES L. JONES.
HOWARD S. McILVAIN.
